(57) CLAIM

I claim, an ornamental design for an herb rack, as shown and described.

DESCRIPTION

FIG. 1 is a perspective view of an herb rack, showing my new design;

FIG. 2 is a front view of FIG. 1;

FIG. 3 is a rear view of FIG. 1;

FIG. 4 is a left-side view of FIG. 1;

FIG. 5 is a right-side view of FIG. 1;

FIG. 6 is a top view of FIG. 1; and,

FIG. 7 is a bottom view FIG. 1.

The broken lines in the drawings depict portions of the herb rack that form no part of the claimed design.
